FACTORY FABRICATED ROUGH PLUMBING UNIT

Filed Nov. 19, 1932

UNITED STATES PATENT OFFICE

2,027,371

FACTORY FABRICATED ROUGH PLUMBING
UNIT

Robert L. Davison, New York, N. Y., assignor to
John B. Pierce Foundation, New York, N. Y., a
corporation of New York

Application November 19, 1932, Serial No. 643,324

12 Claims. (Cl. 4—211)

The invention relates to factory fabricated rough plumbing units.

An object of the invention is to provide a unitary assembly of waste and air vent pipes and connector members for the discharge and venting of a plurality of fixtures such as closet bowl, wash stand, sink, bath or wash tub, and the like. Preferably, the unit is arranged to provide for substantially full discharge of such fixtures singly and two or more simultaneously whereby each discharge flow is effected by full venting and without substantial retardation, and, in addition, the trapping against the escape of sewer and/or other foul gases is insured during the stage of absence of fixture discharge as well as during fixture discharge.

A particular feature of the unit is its adaptability to factory fabrication, thus insuring uniformity of effective sealing quality of the respective joints, the resulting interconnected structure, as well as most efficient spacing and interconnection relationship of the member parts of the unit.

An advantageous feature of the factory fabricated embodiment of the invention resides in the employment of wrought metal such as copper, copper alloys including brass, and the like for the pipe and fitting members, which are preferably interconnected by sweat joints, i. e., by the employment of telescoped connections providing for clearances of reduced dimension to effect capillary flow of the solder or other bonding medium during the stage of bonding, the solder or equivalent congealing and effecting a sturdy joint affording proof against liquid and gas leakage and also against rupture due to mechanical forces.

In the most preferred forms of the invention, the unit provides for the assembly of a horizontally extending, slightly inclined waste pipe section, toward the free end of which are provided connector members for the discharge and overflow of a bath or wash tub; this horizontal pipe section preferably includes an individual trap member. In addition, the preferred embodiments include a Y-fitting or equivalent connector member communicating at its one upper end with the aforesaid horizontally extending pipe section and at its other upper end with a vertically rising air-vent-waste-pipe section, the lower opening of the Y-fitting communicating with a waste or soil line. Connected with an intermediate portion of the horizontally extending pipe section is a set of combined air-vent-waste-pipe sections, each preferably vertical in position, and

providing for connection at an upper end with an upper disposed waste line and/or with the outer atmosphere for venting purposes.

Means are provided in the unit for the discharge of a closet bowl, preferably into a portion of the horizontally extending discharge pipe section located intermediate the combined air-vent-waste-pipe section and preferably by means of a half-siphon-leg connector member; the connection of the lower end of the half-siphon-leg connector member is preferably through an enlargement pipe section, such as an enlargement T fitting, thereby providing for increased effective volume to insure continuity of substantially full flow through the half-siphon-leg member in the event of simultaneous discharge of one or more other fixtures.

In any stage of simultaneous discharge of any two or more fixtures, assembled pursuant to my invention, venting to afford free flow of the respective and joint discharges of the two or more fixtures is had without creating any substantial vacuum or pressure differential tending to or causing a break in the seals in the respective traps, thereby fully complying with standard regulations and precluding the escape of stack or other foul gases at all stages.

Further features and objects of the invention will be more fully understood from the following detail description and the accompanying drawing, in which

Fig. 1 is a perspective elevation of a fabricated unit embodying a preferred form of the invention;

Fig. 2 is a detail side elevation, partly in vertical central section, of the half-siphon-leg member and the wall-on type of closet bowl shown connected to the half-siphon-leg member.

Fig. 3 is a central vertical sectional view on line 3—3 of Fig. 1, on an enlarged scale, and also indicating the connection with a wall-on type closet bowl.

Referring to the drawing, 10 is illustrated as a Y-fitting, its lower end 10a being arranged for connection with a usual soil pipe; its upper right-hand end 10b is arranged for connection with the vertical pipe 11 of the combined air-vent-waste pipe section, as appears more fully hereinafter. The upper left-hand end 10c of the fitting 10 is arranged for connection with the horizontal, 45 slightly inclined pipe section 12, and preferably through an enlargement T 13, or equivalent.

Toward the left-hand end of the pipe section 12 are shown a connector member 14 for the normal discharge of a bath tub or the like and also

connector member 15 for the overflow discharge of such bath tub or the like. Secured to, and as a part of, the pipe section 12 is a trap 16 functioning with the connector members 14 and 15.

Combining with the vertical air-vent-waste-pipe section 11 I arrange the vertical air-vent-waste-pipe section 17, which is connected at its lower end by an offset T 18 with an intermediate portion of the pipe section 12; the upper end of the air-vent-waste-pipe section 17 is connected by the pipe section 18 with an inverted Y 19 or equivalent, the upper end 19a of the same being arranged for connection with an upper section 15 of waste line or directly communicating with the atmosphere.

As principal features of my invention, I provide for the discharge flow of a closet bowl through the enlargement fitting 13, and preferably by means of a half-siphon-leg connector member 20, its lower end 20a being sealingly telescoped interiorly or exteriorly, as preferred, relative to the end 13a of the member 13; its upper end 20b is arranged for connection with a complementary half-siphon-leg, preferably by connection with a wall-on type of closet bowl 21, see Figs. 2 and 3. In the illustrated embodiment, the body of the closet bowl is molded to provide for the half-siphon-leg passage 22. My invention is of particular advantage for the discharge and venting of an assembly of plumbing fixtures inclusive of a wall-on type of closet bowl or other receptacle provided with a trapway having a lateral discharge outlet, such trapway incorporating in its construction an up-leg, i. e. anterior half-siphon-leg forming with the stated half-siphon-leg 22 the siphonic discharge passage of such lateral outlet receptacle.

An especial advantage of the invention resides in the locating of the complete plumbing unit at or above and not below the floor level, indicated by the horizontal line appearing in Fig. 3, thus obviating the relatively enormous costs of cutting wholly through or in part floor material, drilling the floor, supplying thimbles or equivalent cylindrical sheaths for the drilled openings, constructing built-up floors and/or suspended ceilings, necessitated by all present and prior art plumbing systems.

Combined with the above, I further provide one or more connector members for the discharge of, say, a wash stand and/or laundry tub; the connector member 23 and trap 24 illustrate a suitable connection for a wash stand, and the connector member 25 and trap 26 illustrate a suitable connection for a laundry tub.

In a like manner, connection may be afforded for a kitchen sink, such as a connector member 27 and trap 28.

In the specific unit as illustrated in Fig. 1, the respective connector members are especially designed for the location of a bath room and of a kitchen on opposite sides of a common wall, such arrangement being embodied in a "model" house arrangement. However, it will be understood that the specific types of fixtures and the specific spacing of the essential parts of the plumbing unit may be varied as preferred.

As an essential part of the invention, the joint 70 use of the lower extension of the air-vent-waste-pipe section 11, inclusive of the connector member 10, together with the connector member 13 and the half-siphon-leg member 20 constitute a siphon discharge means for a closet bowl, in combination with the combined vertical pipe section

11 and vertical pipe section 17, and the upper interconnecting pipe section 18. Either or both the combined vertical pipe sections 11 and 17 serve as a waste line section for another fixture, such as a wash stand and/or laundry tub, and/or 5 kitchen sink, whereby during the stage of discharge of one, two or more, complete venting is effected simultaneously with substantially complete discharge of the respective fixtures, as well as for the complete venting and discharge of the 10 fixtures one at a time.

In the particular unit illustrated in the drawing, there is provided in addition, the complete venting and full discharge of a bath tub simultaneously with one or more of the aforesaid fixtures, and also for single discharge.

As an additive feature of my unit, I arrange the enlargement member 13 to have its opening 13a of effectively enlarged bore, namely, of the enlarged diameter indicated by the arrowed dash line 13b as compared with the lesser diameter of the lower end of the half-siphon-leg connector member 20, indicated by the arrowed dash line 20c, see Fig. 3, the increased area providing for an increased capacity of the member 13 during 25 the stage of discharge of the closet bowl through the half-siphon-leg simultaneously with the discharge of one or more of the aforesaid fixtures.

Preferably, the assembled pipe sections and fittings are connected to one another by "sweat" 30 joints, that is, by mutually telescoping the respective abutting ends and sealing and securing the same by solder or other suitable bonding medium which upon cooling attains solid state at ordinary temperatures.

Also, preferably, I employ copper, its alloys, or other suitable thin wrought metal for the pipe sections and fittings, thereby particularly minimizing the total weight of the unit. Reduced weight of the unit imparts portability and renders 40 the unit of especial adaptability for factory fabrication.

In factory fabrication of the unit, the respective extents of projection of the various discharge connector elements are arranged to be substantially 45 uniform on the respective opposite sides of a plane passing through the central elements, the last named being the air-vent-waste-pipe sections 11, 17. For example, in the unit illustrated in Fig. 1, the extent of projection of the connector member 50 24 is substantially the same as that of the half-siphon-leg 20 from the plane passing through the air-vent-waste-pipe sections 11, 17. Similarly, the extent of projection of the connector member 26 is substantially the same as that of 55 the connector member 27. Such uniform extent of projection greatly facilitates enclosing the unit in a crate, shook, or the like. In such relation, in general, the connector members on the respective opposite sides of the central plane of the 60 unit serve as braces to position the unit as a whole within the shipping or storing container, and function as such substantially without the necessity of auxiliary braces, or other staying means.

Proper factory fabrication of unit also insures 65 rigidity of the joints to withstand not only the mechanical stresses incident in the use of the unit when installed, but also those encountered in transit and handling in the shipment of the unit to the location of installation.

Units embodying my invention lend themselves 70 applicable as a part of and supplemental to a combined wall structure unit for kitchen and bathroom, in turn combined with the necessary service pipes for the respective fixtures.

From the above, it appears that my invention results in a combined assembly of waste and air-vent pipes or pipe sections coordinated to insure full flow discharge of the fixtures, singly, and 5 two or more jointly, and at all stages affording the corresponding extents of venting and the absence of pressure differential upon the seals provided by the traps in the unit structure or in any fixture per se.

10 In relation to the closet bowl and its siphon connection with the unit, whether of the half-siphon leg type or of any suitable regulation or other approved type, the fitting 16 and the therewith connected waste line or stack combine to effectually complete the siphon structure, which result is attained whether the T-connector 13 be of the enlarged capacity type as above described or of the regulation or other approved type.

Whereas I have described, preferred embodiments of my invention somewhat in detail, it is to be understood that many changes and modifications may be made without departing from the spirit of the invention.

I claim:

25 1. In combination with a receptacle provided with a trapway having a lateral discharge, of a substantially horizontal extending member, trap means connected to said horizontally extending member, a vertically extending combined air-vent and water-pipe member, a Y-fitting connecting said vertical member with said horizontally extending member, a vertically extending combined air-vent and waste-pipe member connected at a lower portion to said horizontally extending member remote from the connection of the latter with said first-named combined air-vent and waste-pipe member and connected at an upper portion to said first-named combined air-vent and waste-pipe member, and a half-siphon-leg connector member communicating with said substantially horizontally extending member.

30 2. In combination with a receptacle provided with a trapway having a lateral discharge, of a substantially horizontally extending member, trap means connected to said horizontally extending member, a vertically extending combined air-vent and water-pipe member, a Y-fitting connecting said vertical member with said horizontally extending member, a vertically extending combined air-vent and waste-pipe member connected at a lower portion to said horizontally extending member remote from the connection of the latter with said first-named combined air-vent and waste-pipe member and connected at an upper portion to said first-named combined air-vent and waste-pipe member, and a half-siphon-leg connector member communicating directly with said substantially horizontally extending member and intermediate said two vertically extending members.

35 3. In combination with a receptacle provided with a trapway having a lateral discharge, of a substantially horizontally extending member, trap means connected to said horizontally extending member, a vertically extending combined air-vent and water-pipe member, a Y-fitting connecting said vertical member with said horizontally extending member, a vertically extending combined air-vent and waste-pipe member connected at a lower portion to said horizontally extending member remote from the connection of the latter with said first-named combined air-vent and waste-pipe member and connected at an upper portion to said first-named combined air-vent and waste-pipe member, a T fitting connected

40 with said horizontally extending member, and a half-siphon-leg connector member communicating with said T fitting.

4. In combination with a receptacle provided with a trapway having a lateral discharge, of a substantially horizontally extending member, trap means connected to said horizontally extending member, a vertically extending combined air-vent and water-pipe member, a Y-fitting connecting said vertical member with said horizontally extending member, a vertically extending combined air-vent and waste-pipe member connected at a lower portion to said horizontally extending member remote from the connection of the latter with said first-named combined air-vent and waste-pipe member and connected at an upper portion to said first-named combined air-vent and waste-pipe member, a T fitting having a relatively enlarged diameter adjacent one of its openings connected directly with said horizontally extending member intermediate said two vertically extending members, and a half-siphon-leg connector member connected with said one opening of the T fitting.

45 5. In combination with a receptacle provided with a trapway having a lateral discharge, of a substantially horizontally extending member, trap means connected to said horizontally extending member, a vertically extending combined air-vent and water-pipe member, a Y-fitting connecting said vertical member with said horizontally extending member, a vertically extending combined air-vent and waste-pipe member connected at a lower portion to said horizontally extending member remote from the connection of the latter with said first-named combined air-vent and waste-pipe member and connected at an upper portion to said first-named combined air-vent and waste-pipe member, discharge and trap connector members communicating with each of said two vertically extending members, and a half-siphon-leg connector member communicating with said substantially horizontally extending member intermediate said plurality of vertically extending members.

6. In combination with a receptacle provided with a trapway having a lateral discharge, of a substantially horizontally extending member, trap means connected to said horizontally extending member, a vertically extending combined air-vent and water-pipe member, a Y-fitting connecting said vertical member with said horizontally extending member, a vertically extending combined air-vent and waste-pipe member connected at a lower portion to said horizontally extending member remote from the connection of the latter with said first-named combined air-vent and waste-pipe member and connected at an upper portion to said first-named combined air-vent and waste-pipe member, a T fitting having a relatively enlarged diameter adjacent one of its openings communicating with said horizontally extending member, discharge and trap connector members communicating with each of said two vertically extending members, and a half-siphon-leg connector member connected with said one opening of the T fitting.

7. In combination with a receptacle provided with a trapway having a lateral discharge, of a substantially horizontally extending member, trap means connected to said horizontally extending member, a vertically extending combined air-vent and water-pipe member, a Y-fitting connecting said vertical member with said horizontally extending member, a vertically extending combined air-vent and waste-pipe member, a T fitting connected

- air-vent and waste-pipe member connected at a lower portion to said horizontally extending member remote from the connection of the latter with said first-named combined air-vent and waste-pipe member and connected at an upper portion to said first-named combined air-vent and waste-pipe member, a T fitting connected with said horizontally extending member intermediate said two vertically extending members, a connector member for the discharge of the fixture communicating adjacent the free end of the horizontally extending member, and a half-syphon-leg connector member communicating with said T fitting.
8. In combination with a receptacle provided with a trapway having a lateral discharge, of a substantially horizontally extending member, trap means connected to said horizontally extending member, a vertically extending combined air-vent and water-pipe member, a Y-fitting connecting said vertical member with said horizontally extending member, a vertically extending combined air-vent and waste-pipe member connected at a lower portion to said horizontally extending member remote from the connection of the latter with said first-named combined air-vent and waste-pipe member and connected at an upper portion to said first-named combined air-vent and waste-pipe member, a T fitting having a relatively enlarged diameter adjacent one of its openings, a connector member including trap means for the discharge of the fixture communicating adjacent the free end of the horizontally extending member, and a half-syphon-leg connector member connected with said one opening of the T fitting.
9. In combination with a receptacle provided with a trapway having a lateral discharge, of a substantially horizontally extending member, trap means connected to said horizontally extending member, a vertically extending combined air-vent and water-pipe member, a Y-fitting connecting said vertical member with said horizontally extending member, a vertically extending combined air-vent and waste-pipe member connected at a lower portion to said horizontally extending member remote from the connection of the latter with said first-named combined air-vent and waste-pipe member and connected at an upper portion to said first-named combined air-vent and waste-pipe member, discharge and trap connector members communicating respectively with said two vertically extending members, a connector member including trap means for the discharge of the fixture communicating adjacent the free end of the horizontally extending member, and a half-syphon-leg connector member communicating with said substantially horizontally extending member intermediate said two vertically extending members.
10. In combination with a receptacle provided with a trapway having a lateral discharge, of a substantially horizontally extending member, trap means connected to said horizontally extending member, a vertically extending combined air-vent and water-pipe member, a Y-fitting connecting said vertical member with said horizontally extending member, a vertically extending member, a vertically extending combined air-vent and waste-pipe member connected at a lower portion to said horizontally extending member remote from the connection of the latter with said first-named combined air-vent and waste-pipe member and connected at an upper portion to said first-named combined air-vent and waste-pipe member, a T fitting connected with said horizontally extending member intermediate said two vertically extending members, a connector member including trap means for the discharge of the fixture communicating adjacent the free end of the horizontally extending member, and a half-syphon-leg connector member communicating with said substantially horizontally extending member intermediate said two vertically extending members.
11. In combination with a receptacle provided with a trapway having a lateral discharge, of a substantially horizontally extending member, trap means connected to said horizontally extending member, a vertically extending combined air-vent and water-pipe member, a Y-fitting connecting said vertical member with said horizontally extending member, a vertically extending combined air-vent and waste-pipe member connected at a lower portion to said horizontally extending member remote from the connection of the latter with said first-named combined air-vent and waste-pipe member and connected at an upper portion to said first-named combined air-vent and waste-pipe member, a T fitting connected with said horizontally extending member, discharge and trap connector members communicating respectively with said two vertically extending members, a connector member including trap means for the discharge of the fixture communicating adjacent the free end of the horizontally extending member, and a half-syphon-leg connector member communicating with said substantially horizontally extending member intermediate said two vertically extending members.
12. In combination with a receptacle provided with a trapway having a lateral discharge, of a substantially horizontally extending member, trap means connected to said horizontally extending member, a vertically extending combined air-vent and water-pipe member, a Y-fitting connecting said vertical member with said horizontally extending member, a vertically extending combined air-vent and waste-pipe member connected at a lower portion to said horizontally extending member remote from the connection of the latter with said first-named combined air-vent and waste-pipe member and connected at an upper portion to said first-named combined air-vent and waste-pipe member, a T fitting having a relatively enlarged diameter adjacent one of its openings, discharge and trap connector members communicating respectively with said two vertically extending members, a connector member including trap means for the discharge of the fixture communicating adjacent the free end of the horizontally extending member, and a half-syphon-leg connector member connected with said one opening of the T fitting.

ROBERT L. DAVISON.
